UNITED STATES PATENT OFFICE.

FREDERICK I. CANNON, OF BEDFORD, OHIO.

PUMP.

1,316,558.

Specification of Letters Patent. Patented Sept. 23, 1919.

Application filed January 13, 1919. Serial No. 279,806.

To all whom it may concern:

Be it known that I, FREDERICK I. CANNON, a citizen of the United States, residing at Bedford, in the county of Cuyahoga and State of Ohio, have invented certain new and useful Improvements in Pumps, of which the following is a specification.

This invention relates to improvements in pumps and is more particularly designed for use in vending oils or other liquids directly from barrels or other containers. The primary object of the invention is to provide a simple and effective device or apparatus of the character set forth, that can be connected with a barrel or other container for the purpose of drawing the liquid from said container and delivering it as desired.

With this and other apparent objects in view, the invention consists in the construction, combination and arrangement of the parts hereinafter described and particularly pointed out in the appended claims when compared or considered in connection with the accompanying drawings, which are made a part of the specification, similar characters of reference being employed to designate corresponding parts.

In the said drawings Figure 1 is a sectional elevation of an embodiment of the improved pump, showing its application to a barrel.

Fig. 2 is a plan section taken on line 2—2, Fig. 1, and Fig. 3 is a section taken on line 3—3, Fig. 1.

Fig. 4 is an outline elevation illustrating a modification of a portion of the pumping mechanism, and Fig. 5 is a fragmentary view of the modification in direction of arrow, Fig. 4, and showing the piston and connecting rod in a different position.

A pump provided with my improvement will include a cylinder 1 provided with a plunger 2, which has a reciprocating movement in said cylinder. The lifting of the plunger serves to draw grease, oil, or other liquid from a container B, through the pipe 3 into the cylinder, and when depressed it forces the liquid, thus previously admitted, out of the cylinder through an outlet pipe 4, leading to any desired point of discharge, provision being made at 5 for the attachment of hose, not shown.

While the elements above mentioned and their operating means are more or less already in common use, they are necessary

factors in the operation of the improved pump. The improvement however lies in the novel arrangement and operation of the lower parts including the valves and their co-action with the said common elements.

The base or cylinder support 6 is adapted to rest on the container B and is provided with a pipe 3 that depends into said container, as shown in Fig. 1. A chamber 7 is provided in the member 6, said chamber being in communication with the interior of the cylinder 1. A secondary chamber 8 also communicates with the cylinder through the port 9. The chamber 8 is connected with the inlet pipe 3, and ports 10 connect chamber 8 with chamber 7. The outlet 4 connects with chamber 8 above the ports 10. A valve member 11, preferably hollow as shown, is provided. Said member is adapted to slide vertically in the chamber 8, and is actuated by the action of the plunger 2.

In the embodiment illustrated in Figs. 1, 2 and 3, the plunger 2 is mounted on the lower end of a vertical shaft or piston rod 12, between the fixed collars 13 and 14, suitable ball-bearings 15 being provided to allow the rod to turn freely in the plunger. The piston rod 12 extends through the head 16 and is provided with right and left hand screw-threads 17. A bevel gear 18 is mounted with suitable ball-bearings 19, on the head 16, and the piston rod 12 extends through the bore of said gear. A swiveled segmental projection 20 is provided in the bore of the gear 18, said projection being adapted to travel in the right and left hand screw-threads 17 which intersect each other, and at the end portions they communicate in such manner that when the projection 20 reaches the extremity of one screw-thread it will automatically adjust itself and pass into the other screw-thread, whereby the rotary motion of the rod 12 imparts a reciprocating motion to the collars 13 and 14, and thus the plunger 2 is reciprocated. This mechanical movement is not new and has been employed heretofore in pump construction, therefore I do not claim it specifically.

A companion bevel gear 21 is mounted on the head 16 and is in mesh with the gear 18. A crank 22 provides means for driving the gears.

When the plunger 2 is raised through the medium of the mechanism above described, the suction lifts the valve 11, thereby uncovering the ports 10, and the liquid

is drawn from the pipe 3 into the cylinder through said ports 10 and the chamber 7. As the valve 11 uncovers the ports 10 it covers the mouth 4^a of the outlet member 4.

5 When the plunger 2 is depressed, the valve 11 is forced downward, thereby closing the ports 10 and the pipe 3. The mouth 4^a is uncovered and communication is established from the cylinder, through port 9 and chamber 8 to the outlet, and liquid that has previously been drawn into the cylinder is forced out through the outlet 4. A check valve 23 is provided, said check valve being adapted to open on the downward stroke of 15 the plunger, and to close on the up stroke of said plunger.

The exact quantity of liquid discharged in each full stroke will be determined by the extent of the plunger movement. The 20 desired quantity being predetermined, the capacity of the cylinder and the length of stroke are calculated, and the pump is designed and assembled accordingly.

In the modification illustrated in Figs. 4 25 and 5, the valve construction and operation is identical with the preferred form as set forth, but the plunger driving mechanism is different. In this construction the piston rod 24 is reciprocated through the medium 30 of a connecting rod 25 connected with a crank 26 which is driven by a manipulating member 27, the rod 24 being guided by a yoke 28.

I do not limit my invention to the specific 35 construction as illustrated and described, as many modifications in structure may be made within the scope of the claims without departing from the spirit of the invention.

40 What I claim and desire to secure by Letters Patent is:

1. In a pump, the combination of a cylinder; a reciprocating piston operating in said cylinder; means for actuating said 45 piston; a base member for the cylinder; an inlet chamber in the base, communicating with the cylinder; an outlet chamber in the base communicating with the cylinder; an outlet duct connected with the outlet chamber; a check valve in the outlet duct; an inlet port at the lower extremity of the outlet chamber; ports from the inlet chamber to the outlet chamber below the outlet duct; a 50 slideable valve fitted in the outlet chamber, said valve being actuated by the suction and compression caused by the reciprocating movement of the piston, thereby opening the ports that communicate with the inlet chamber and close the outlet duct 55 on the suction stroke, and close the inlet ports and open the outlet duct on the alternate compression stroke.

2. In a pump, the combination of a cylinder; a reciprocating piston operating in said cylinder; means for actuating said piston; a base member for the cylinder; an inlet chamber in the base, communicating 65 with the cylinder; an outlet chamber in the base, communicating with the cylinder; an outlet duct connected with the outlet chamber; a check valve in the outlet duct; an inlet port at the lower extremity of the 70 outlet chamber; an inlet pipe connected with the last named port; ports from the inlet chamber to the outlet chamber below the outlet duct; a slideable valve fitted in the outlet chamber, said valve being actuated 75 by the suction and compression caused by the reciprocating movement of the piston for alternately opening and closing the inlet ports, and the outlet duct.

3. In a pump, the combination of a cylinder; a reciprocating piston operating in said cylinder; means for actuating said piston; a base member for the cylinder; an inlet chamber in the base, communicating 80 with the cylinder; an outlet chamber in the base, communicating with the cylinder; an outlet duct connected with the outlet chamber; a check valve in the outlet duct; an inlet port at the lower extremity of the outlet chamber; an inlet pipe connected with 85 the last named port; ports from the inlet chamber to the outlet chamber below the outlet duct; a slideable valve fitted in the outlet chamber, said valve being actuated by the suction and compression caused by 90 the reciprocating movement of the piston for alternately opening and closing the inlet ports, and the outlet duct.

4. In a pump, the combination of a cylinder; a piston operating in said cylinder; 100 rotary driving mechanism so arranged and connected with the piston as to impart a reciprocating movement to said piston; a base member for the cylinder; an inlet chamber in the base, communicating with the cylinder; an outlet chamber in the base, communicating with the cylinder; an outlet duct connected with the outlet chamber; an inlet port at the lower extremity of the outlet chamber; an inlet pipe connected with 105 the last named port; ports from the inlet chamber to the outlet chamber below the outlet duct; a check valve in the outlet duct; a slideable valve fitted in the outlet chamber, said valve being actuated by the suction and compression caused by the reciprocating movement of the piston for alternately opening and closing the inlet ports, and the outlet duct.

5. In testimony whereof I affix my signature. 110

FREDERICK I. CANNON.
